UNITED STATES PATENT OFFICE.

ELLA GREENBERG, OF NEW YORK, N. Y.

COMBINED UMBRELLA AND PACKAGE CARRIER.

Application filed July 13, 1926. Serial No. 122,184.

My invention relates to articles of personal convenience, and specifically to devices which are adapted for use either as an umbrella or sunshade, or as a package carrier, 5 the same being capable of being changed from one of these devices to the other by an easily accomplished adjustment of parts.

The principal object of my invention is to provide an article of the kind mentioned 10 which shall be simple in construction and easy of management, so as to be readily transformed from the arrangement of its parts which permits it to be used as an umbrella, to another arrangement of such parts 15 which permits it to be used as a package carrier.

The invention consists in the novel construction, arrangement and combination of various elements and parts as set forth in 20 the claims hereof, one embodiment of the same being illustrated in the accompanying drawings and described in this specification.

In the accompanying drawings,

Fig. 1 is a side elevation of an article embodying my invention, the same being shown 25 with the parts arranged in such a way as to constitute an umbrella;

Fig. 2 is a bottom view of the same, that is, looking upward along the handle as 30 shown in Fig. 1 to the inner or lining side of the umbrella covering;

Fig. 3 is a vertical section of my invention, in a position reversed from that shown in Fig. 1, the parts being arranged in the position adapting the article for use as a package carrier, the coverings, however, being removed so as to clearly show the internal construction; and

Fig. 4 is a similar vertical section but 40 showing the parts arranged in a position intermediate the positions shown in Fig. 1 and Fig. 3, that is, when the device is being changed from umbrella to package carrier or vice versa.

In carrying my invention into effect in the embodiment thereof which I have selected for description in this specification and illustration in the accompanying drawings, I provide a stick or handle 11 analogous to the 45 handle of an ordinary umbrella. This may have at one end—the lower end in Fig. 1 but the upper end in Figs. 3 and 4—a knob 12 and ring 13, or such other ornamental carrying device as may be desired. At the other 50 end of the handle—the upper end in Fig. 1 and the lower end in Figs. 3 and 4—is a cup-

shaped securing member 14 adapted to engage the ends of the swinging ribs in a manner shown in Fig. 3, when the parts are placed in the position there shown in order 60 to adapt the device for use as a package carrier.

Referring more particularly now to Fig. 4, which is perhaps best adapted to illustrate the interrelation of ribs, stretchers and sliding devices which form special novel features of my invention, it will be seen that in this view the invention simulates in some degree an ordinary umbrella, but upside down. As in an ordinary umbrella, there 70 is a fixed sleeve at the top of the handle (shown in this figure as being at the bottom), which sleeve is designated 16. There is also, as in an ordinary umbrella, a sliding sleeve 17. From opposite sides of this sliding sleeve 17 extend laterally in each direction parallel rods, the nature and location of which cannot be clearly understood from Fig. 4 alone, but will be better understood by collating said figure with Fig. 2, where 80 the said pair of parallel rods, which are designated 18, are represented in dotted lines, they being on the other side of the flaps 19 hereafter to be described. Supported at the ends of these parallel rods is a ring 20.

Pivotedly connected to the sleeve 16 at the upper end of the stick 11 (lower end in Figs. 3 and 4) are rods 21. These are analogous to the stretchers of an ordinary umbrella, but are unlike such stretchers in being secured to an immovable sleeve. Pivotedly attached by their inner ends at suitable intervals to the ring 20, are rods 22. These are analogous to the ribs of an ordinary umbrella, but are unlike such ribs in being operatively connected with a sliding sleeve. It 90 will be seen that the structure of my invention is in some respects the reverse of that of the ordinary umbrella. In the ordinary umbrella, one end of each stretcher is pivotedly secured to a sleeve which slides upon the umbrella stick, and the other end of each stretcher is secured to one of the ribs at a point intermediate the ends of the rib, one 95 end of each rib being pivotedly connected to a sleeve fast at the upper end of the umbrella stick and the other end of each rib being free, whereas in my invention one end of each stretcher is pivotedly secured to a sleeve fast at the upper end of the stick and the 100 other end of each stretcher is pivotedly secured to one of the ribs at a point interme-

2
diate the ends of the rib, one end of each rib being operatively connected with a sleeve which slides on the umbrella stick, the other end of each rib being free. An ordinary umbrella in its closed position has the inner ends of its ribs held pivotally by the fixed sleeve and the outer ends of the ribs adjacent the lower end of the umbrella stick, and such an umbrella is raised by moving upward the sliding sleeve so that the stretchers spread the ribs outward from the umbrella stick into the open position. My invention in its closed position, which, however, is not really entirely closed, but closed as much as is intended (best shown in Fig. 3), has the inner ends of its ribs 22 operatively connected with a sliding sleeve at the lower end of the umbrella stick (upper in Figs. 3 and 4) and the outer ends of the ribs adjacent the upper end of the umbrella stick, and my form of umbrella is raised by moving upward the sliding sleeve 17 so that the ribs 22 are spread outward by the stretchers 21, passing through the intermediate position shown in Fig. 4, and finally coming into the position shown in Fig. 1.

In Figs. 1 and 2 I have shown the skeleton structure heretofore described, as provided with coverings. In Fig. 1 the outer covering 23 is shown, being formed in the usual way in segments united by seams 24. A part of this outer covering is broken away so as to show the inner covering or lining 25. This inner covering or lining 25 is also shown on the inside view of the device in Fig. 2, which is also composed of segments united together by seams 26, and being broken away to show the outer covering 23. At the broken away portions in Figs. 1 and 2, a part of a rib 22 appears; the remainder of said ribs do not appear in Figs. 1 and 2, because they are concealed between the coverings 23 and 25; portions of three of the stretchers 21, however, appear in Fig. 2, being inside of the outer covering 23 and being shown by the opening up of one of the flaps 19 as hereinafter described.

The covering 23, which has been spoken of as the outer covering and which corresponds to the single covering of an ordinary umbrella, is shown on the outside of the skeleton frame in Fig. 1. In this position the part of the skeleton frame which supports this covering 23 and which thus presents the form of the device analogous to an ordinary umbrella, consists of the ribs 21 which are pivotally connected at their inner ends to the sleeve 16 and at their outer ends to the ribs 22, and the outer portion, approximately one half, of the ribs 22. In other words, when the device is in this position, the ribs 21 and the outer portions of the ribs 22, taken together, correspond to the ribs of an ordinary umbrella, and in that position the inner portions of the ribs 22,

that is to say, the portions which are pivotally connected to the ring 20, correspond to the stretchers of an ordinary umbrella. The covering 23 is secured to this composite rib above mentioned, by stitches at suitable intervals, as for instance one set of stitches at the sleeve 16, another set of stitches approximately at the point where the ribs 21 are pivoted to the ribs 22, and another set of stitches near the outer ends of the ribs 22, as in an ordinary umbrella. In other words, the device in this position exactly corresponds to an ordinary umbrella except that the ribs are composed of two pivotally connected sections 21 and 22, a part of each rib 22 serving as a part of the rib and another part of each rib 22 serving as the stretcher. The covering 25, on the other hand, is, as already stated in the last paragraph and as shown in Fig. 2, which is a view of the inside of the device while in a partly opened and partly closed position, corresponding to the position of the frame shown in Fig. 4, attached to the ring 20 and then extends downward therefrom, as a series of segments 20 united at the seams 26 and secured at those seams to the ribs 22. When the skeleton frame is in the position shown in Fig. 4, the covering 25 would, if it were shown in said figure, be on the side of said ribs 22 toward the handle 12, and when the device is to be used as a package container the ring 17 is slid along the stick 11 towards and up to the handle 12, which causes the ribs 22 to occupy the position shown in Fig. 3, the outer ends of said ribs being then gathered into the cup-shaped guard or holder 14, and in that case the covering 25 would appear as a ruffled or fluted bag surrounding the outside of the whole device, to which access may be had by lifting the flaps 19 into the position shown in dotted lines in Fig. 3, the space inside of the ribs 22 and 21 then constituting the package receptacle, in which position the covering 23, which is the outer covering of the device when it is used as an umbrella in the form shown in Fig. 1, is inside, and the covering 25 outside. It will be understood of course that the coverings 23 and 25 will be secured together by a suitable seam along such a line as may be proper.

When my invention is to be used as a package carrier, the parts are placed in the position and mutual relations shown in Fig. 3. It will be seen that hinged on the rods 18 are semicircular lids or flaps 19. These are shown in dotted line elevated or opened fully in Figs. 3 and 4, and one of them is shown partly elevated in Fig. 2, for the purpose of disclosing portions of the stretchers 21. It will be understood that the skeleton ribs and stretchers as shown in Fig. 3 are when in use covered by the outer covering 23 extending from the end of the stick nearly to the ends 130

of the ribs 22, and the inner covering 25 extending from the ring 20 likewise nearly to the end of the ribs 22, as shown in Figs. 1 and 2. In the position shown in Fig. 3, 5 the outer ends of the ribs 22 are gathered up into the bowl-shaped guard 14 and are securely held there so as to construct the package carrier, which as will be readily seen is then formed in the inside of the device, access thereto being had by raising the 10 flaps or doors 19.

If desired, a mirror, vanity box, or other receptacle or device, may be secured to either or both of the flaps 19.

15 The operation of my invention has been already necessarily pointed out in connection with the description of the construction of the invention, and nothing further need be said as to the same.

20 The advantages of the device also will be obvious from an inspection of the drawings in connection with what has been said with regard to its construction.

I do not limit myself to the exact form of 25 construction and arrangement of parts which is illustrated in the drawings and described in this specification, as it will be obvious to those skilled in the art to which this invention relates, that many modifications 30 in detail and various arrangements of the elements of the invention, can be made without departing from the spirit and scope of the invention.

Having thus described my invention, what 35 I claim as new and desire to secure by Letters Patent is as follows:

1. A combined umbrella and package carrier, comprising a stick, a sleeve at one end of said stick, rods pivotally secured at their 40 inner ends to said sleeve, another sleeve slideable on said stick, a bar secured to said slideable sleeve and extending laterally in opposite directions therefrom, a ring supported by the outer ends of said bar, rods pivotally 45 connected at their inner ends to said ring and pivotally connected intermediate their ends to the outer ends of said first-named rods.

50 2. A combined umbrella and package car-

rier, comprising a stick, a sleeve at one end of said stick, rods pivotally secured at their inner ends to said sleeve, another sleeve slideable on said stick, rods operatively connected at their inner ends to said sleeve and 55 pivotally connected intermediate their ends to the outer ends of said first-named rods, a fabric associated with said first-named rods and last-named rods and adapted when said rods are fully extended to constitute an outside covering thereon, extending from said fixed sleeve nearly to the outer ends of said last-named rods, whereby an umbrella is formed, and another fabric associated with 60 said last-named rods and adapted when said rods are fully extended to constitute an inner covering thereon, extending from the inner ends nearly to the outer ends of said last-named rods and adapted when said rods are closed to form the upper part of a bag 70 or receptacle for packages or the like.

3. A combined umbrella and package carrier, comprising a stick, a sleeve at one end of said stick, rods pivotally secured at their inner ends to said sleeve, another sleeve slideable on said stick, a bar secured to said slideable sleeve and extending laterally in opposite directions therefrom, a ring supported by the outer ends of said bar, rods pivotally 75 connected at their inner ends to said ring and pivotally connected intermediate their ends to the outer ends of said first-named rods, a fabric associated with said first-named rods and last-named rods and adapted when said rods are fully extended 80 to constitute an outside covering thereon, extending from said fixed sleeve nearly to the outer ends of said last-named rods, whereby an umbrella is formed, and another fabric associated with said last-named rods and 85 adapted when said rods are fully extended to constitute an inner covering thereon, extending from said ring nearly to the outer ends of said last-named rods and adapted when said rods are closed 90 to form the upper part of a bag or receptacle for packages or the like.

In witness whereof I have hereunto signed my name this 1st day of July 1926.

ELIA GREENBERG.
